(57) **CLAIM**

The ornamental design for a nuclear power plant utility cart,
as shown and described.

DESCRIPTION

FIG. 1 is a perspective view of a nuclear power plant utility cart showing our new design;
FIG. 2 is a front view thereof;
FIG. 3 is a rear view thereof;
FIG. 4 is a left side view thereof;
FIG. 5 is a right side view thereof;
FIG. 6 is a bottom view thereof;
FIG. 7 is a top view thereof;
FIG. 8 is a perspective view of another embodiment of a
nuclear power plant utility cart;
FIG. 9 is a front view thereof;
FIG. 10 is a rear view thereof;
FIG. 11 is a left side thereof;
FIG. 12 is a right side thereof;
FIG. 13 is a bottom view thereof; and,
FIG. 14 is a top view thereof.
